UNITED STATES PATENT OFFICE.

DANIEL W. GOODWIN, OF LYNN, MASSACHUSETTS.

SHOE-STRETCHER.

No. 853,077.

Specification of Letters Patent.

Patented May 7, 1907.

Application filed February 18, 1907. Serial No. 857,886.

To all whom it may concern:

Be it known that I, DANIEL W. GOODWIN, of Lynn, county of Essex, State of Massachusetts, have invented an Improvement in Shoe-Stretchers, of which the following description, in connection with the accompanying drawings, is a specification, like characters on the drawings representing like parts.

This invention relates to that class of shoe stretchers which are formed by dividing the forepart of a last or form of desired shape into two sections, by sawing the same from end to end and top to bottom through the middle thereof, said sections being hinged together at their rear ends, and provided with a spreading device. An inexpensive form of spreading device commonly employed for this purpose comprises a wedge, screw and nut which are loosely held between the sections, so that they may, and often do fall out of position when the sections are opened to a certain extent. Such occurrences cause inconvenience, and, moreover, the insertion of the form into a shoe is rendered somewhat more difficult by the tendency of the sections to swing apart.

My invention has for its object to provide a simple and inexpensive means for hinging the rear end of the sections together which will normally hold said sections in their normal position, so that they may be easily inserted in the shoe, and so that the spreading device will be constantly held in position, and which does not so project beyond the surface of the form, as to interfere with the convenient use thereof. I accomplish these objects by the means shown in the accompanying drawing, in which,

Figure 1 is a top plan view of a shoe stretcher or form provided with my invention. Fig. 2 is a bottom plan view of the heel end portion thereof. Fig. 3 is a longitudinal section on the line 3—3 Fig. 1. Fig. 4 is an elevation of the heel end of the form. Fig. 5 is a detail view of the connecting device ready to be applied.

As shown in the drawing, the form or follower comprises two sections *a* and *b* which are adapted to be fitted together, the meeting faces of said sections lying in a plane which extends longitudinally from top to bottom thereof through the middle portion of the form. Said sections are hinged together at their rear ends in a manner which I will presently describe. The spreading means shown is similar to that ordinarily

employed in devices of this character, comprising the wedge *c* which is swiveled on the front end of a screw-threaded rod *d*, said rod being threaded in a nut *e* mounted in adjacent recesses formed in said sections near the rear ends thereof. The adjacent or meeting faces of the sections are provided with longitudinal grooves in which the wedge *c* is adapted to move, so that, as the wedge is forced forward, the sections will be swung apart at their front end.

In providing the sections with a connection made according to my invention, I first form a recess *f* in contiguous portions of said sections by boring from the middle of the bottom thereof closely adjacent the heel end, and before it is split, said recess extending approximately three-fourths of the way to the top. When the form is split into two sections *a* and *b*, as before described, one-half the recess *f* will be located in one section and one-half in the other section. The wall of the recess next the rear end is cut away or beveled so that the surface of the recess is substantially continuous with the rear end surface of each section.

To connect the form sections according to my invention I provide a strip of spring metal which is stamped or bent so as to form a circular middle portion *g*, which preferably extends through somewhat more than a semi-circle and which is reversely curved at each end and extended to provide ears *g'*, *g''*, which, before they are applied, extend divergently at an acute angle to the adjacent middle portion *g*, as indicated in Fig. 5. Said middle circular portion *g* is inserted in the recess *f* and the ears *g'*, *g''* are rigidly secured to the rear ends of the corresponding sections *a*, *b*, by nails or screws *h*.

In securing the ears *g'*, *g''* to the ends of the sections *a*, *b*, they are swung into the same plane and the intermediate spring portion in acting thereon caused the sections to be swung together, said intermediate portion thus performing the double function of a spring and a hinge.

As the entire spring portion between the ears *g'*, *g''* is gradually curved, the possibility of undue strain being placed on any portion thereof, and of the spring being unduly weakened at any point by bending is avoided. The spring is practically entirely inclosed by the form, so that there are no inconvenient projections to interfere with the insertion and removal thereof in use.

Having thus described my invention, what I claim as new and desire to secure by Letters Patent is:—

1. A shoe form composed of two longitudinal sections having a recess formed in contiguous portions, and at the heel end thereof, a spreading device disposed between said sections and means for yieldingly holding said sections together in their normal position comprising a metal strip having an intermediate curved spring portion disposed in said recess, and a pair of ears extending in opposite directions from the ends of said spring portions and respectively secured to the adjacent ends of said sections, substantially as described.
2. A shoe form composed of two longitudinal sections having a recess formed in contiguous portions, and at the heel end thereof, a spreading device disposed between said sections and means for yieldingly holding said sections together in their normal position comprising a metal strip having an intermediate curved spring portion disposed in said recess, and a pair of ears extending in opposite directions from the ends of said spring portions and respectively secured to the adjacent ends of said sections, substantially as described.

uous portions, and at the heel end thereof, a spreading device disposed between said sections and means for yieldingly holding said sections together in their normal position comprising a metal strip having an intermediate curved spring portion disposed in said recess and reversely curved at the ends of said portion and extended in opposite directions to form ears, and means of securing said ears to the adjacent ends of said sections, substantially as described.

In testimony whereof, I have signed my name to this specification, in the presence of two subscribing witnesses.

DANIEL W. GOODWIN.
